UNITED STATES PATENT OFFICE.

FRANCISCUS HENRICUS REIJNDERS, OF SOESTERBERG, NETHERLANDS, ASSIGNOR OF
ONE-HALF TO NAAMLOZE VENNOOTSCHAP NEDERLANDSCHE SEINTOESTELLEN
FABRIEK, OF HILVERSUM, NETHERLANDS.

DIATHERMY DEVICE.

Application filed October 8, 1923, Serial No. 667,371, and in the Netherlands October 6, 1922.

The present invention relates to apparatuses and devices for locally generating heat, e. g. in living organisms fluids and similar electrically conductive media.

- 5 To this end high frequency alternating currents are generated by means of a triode or valve, of which the grid and the anode are each connected to the glowing filament by means of a conductor whilst their circuits 10 are electrically connected to each other. A high tension source of current is included between the anode and the cathode and the cathode is supplied from a source of current. The frequency of the generated alternating 15 currents is determined by the electric constants of the said circuit. The quantity of energy which may be taken from this apparatus may be varied by coupling a third circuit electrically to one of the two said circuits and by bringing the object or body to be treated in the said third circuit.

The principal characteristic of the invention is that means are provided which completely control and regulate the various 25 physiological phenomena to which the patient is subjected, in accordance with the disease and the sensitiveness of the patient.

Said means are partially contained in the oscillation-generator and partially in the 30 electrode. Thereby it is rendered possible to vary not only the intensity of the oscillations and the frequency, but also the temperature of the electrode and its chemical actions. As is known the very high frequencies cause 35 the so-called skin effect, which consists therein that the alternating currents pass exclusively through the periphery of the conducting body. For certain purposes for instance for surgical purposes, this may be of great 40 advantage; for other purposes for instance for mere "depth heating" it is however a disadvantage as in that case it is desired to operate at a lower frequency. In connection herewith it is pointed out that the said conducting bodies generally have a very small inductance which causes that the skin effect will only occur in a high degree when operating at very high frequency.

45 Further the device is so constructed that it may be connected to the ordinary electric lighting circuit whereby its value for a physician is increased. Also an X-ray tube particularly of the Coolidge type may easily be

connected thereto so that the physician need not buy a special X-ray device.

50 A further characteristic of the device consists in the particular grounding which renders it possible that the physician may touch the patient without danger of shocks. Further irritation phenomena are prevented or 55 regulated by transmitting the generated alternating current to the human body by means of a special electrode.

The electrodes hitherto used consisted of a conducting object, which was brought into contact with the skin. The conducting surface usually consisted of metal, sometimes of a layer of some material or other, soaked in an electrolyte and thus made conductive. As the point of contact always shows a great 70 contact-resistance, a great quantity of heat will be produced at the spot, soon causing the electrode to get a higher temperature than is desirable. Particularly in applying oscillations of a very high frequency this heating 75 will take place at the edges, as in consequence of the so-called "skin effect" the current is pressed to the outside of conducting bodies. This causes at the same time disagreeable irritation phenomena at the places 80 of contact. These drawbacks of the electrodes used hitherto were the reasons that certain diseases could not satisfactorily be treated diathermically and particularly in those cases, where a large supply of energy 85 was necessary, no favourable results could be obtained, such as, for example, with urethritis gonorrhœica.

According to the invention these drawbacks are overcome by using an electrode, 90 which is made of an alloy of various metals, which electrode is intensively cooled at the edges. This can for example be obtained by applying a bent tube round the edge, through which edge a cooling fluid may pass 95 with such a rapidity that the desired temperature is maintained constantly.

Moreover it is possible to avoid irritation phenomena by a suitable choice of the electrode material. It has appeared that such material should not only conduct the electric current well and should be at the same time a good heat-conductor, but that the electrode material should be mechanically soft. Various metals, especially those with a low melting point are suitable for the purpose, such 100

as Wood's-metal, tin, antimony and various metals as are used for bearings. Particularly metals of the tin group and alloys of these metals appear to suit the purpose, whereas, copper appeared to be peculiarly unsuitable.

In this connection it may be observed that for open-wound treatment, the metals must be totally different. It has been found that in that case preference must be given to precious metals.

The device may further be provided with a safety device which automatically takes care that the temperature of the part of the body to be treated is kept within predetermined limits. For instance there may be connected to the electrode a device, the electric properties of which vary in a known manner according to a temperature and which device acts upon the oscillation-generating, the coupling or the cooling of the electrode.

To better understand the nature of the invention a preferred form of a connection, to be used with the apparatus will be described with reference to the accompanying drawing in which—

Figure 1 is a diagram of the electric circuit.

Figures 2 and 3 are side and plan view, respectively, of the fluid cooled electrode.

Figure 4 is a section on the line A—B of Fig. 3.

The current is supplied by conductors 1 and 2 from an ordinary alternating-current lighting-plant. Part of this current passing through the transformer supplies the filament of the triode, which is earthed at 25. Another part of the current is supplied to transformer 4 and passes two circuit controllers 5 and 6 of which the former is a safety-contact which is closed, when the case containing the high-tension-apparatuses is closed, making it impossible to touch these parts, when working. The controller 6 is of the foot operated type by which the physician is enabled, either to connect the apparatus for a short time or for an indefinite period. A condenser 7 is connected across the secondary of the high-tension-transformer 4. One end of the secondary winding is connected through a high-frequency choking-coil 8 to the valve, whereas the other extremity of the secondary is connected to earth through a milliammeter 9, so that with this meter the anode-current can be measured. The coil 8 prevents high-frequency alternating-currents from reaching the transformer 4, whilst the impedance of coil 8 together with the reactance of the condenser 7 prevents the secondary current of transformer 4 from passing through condenser 10 to earth. The generated high frequency currents can pass the condenser 10, which, however, does not allow the rectified

part viz, anode-current to pass. The frequency of the generated oscillations is determined by a closed oscillating-circuit, which consists of a coil 11 and the condensers 12 and 13. A milliammeter 14 indicates the intensity of the pure alternating current generated in this circuit. The valve is connected in a very special way with the oscillation-circuit. The grid of the valve is connected with leakage-resistance 16 via a grid-condenser 15, to the one extremity of coil 11, whereas the filament which is earthed, is connected with point 17 of this coil. The anode or plate of the valve is connected with the coil 11 inductively as well as directly; inductively by means of coil 18, which possesses as a rule many windings of thin wire and the extremity of which is directly connected to point 19 of coil 11. By this device and a good selection of the points 19 and 17 numerous experiments have shown, that the energy used can suddenly be altered within wide ranges without the valve ceasing to generate, so that a continued uninterrupted medical treatment is possible, which is of the utmost importance for the medical results.

The energy used is taken off in this example by means of the adjustable coupling-coil 20. The current led through the conductors 21 and 22 is read on the ammeter 23; at 24 an earth connection is provided, which enables the physician to touch the patient without danger of shocks.

In some cases it is desirable to provide a device, whereby the temperature of the electrode or the treated part of the body is kept constantly within certain limits.

For this purpose the electrode an embodiment of which is illustrated in Figures 2, 3 and 4, is provided with a device for regulating the temperature which is formed by a bent metal tube 26 forming the rim of the electrode and through which a cooling liquid flows.

The two halves of the tube are interconnected by means of the plate 27 of electrode material which is clamped around the tube as is shown in the Figures 3 and 4.

The necessary firmness may be obtained by the parts 28, shown in Fig. 2 which are hingedly connected together at 29 so as to allow some deformation of the electrode. The electrode may by means of resilient sleeves 30 be attached flexibly to a belt or the like surrounding the body of the patient.

Obviously also other arrangements for an automatic regulation of the temperature of the said diathermy are possible.

For clearness sake the main contacts of the diathermy apparatus are closed and opened directly by the relay springs, but it is obvious that in most cases special switches using condensers or resistances across their contacts will be necessary.

Finally the new apparatus can be applied for physiologic-neurologic and pathologic-neurologic research in connection with the extensive variability of the oscillating-frequency, whereby the great advantage is obtained that the irritability as a function of the oscillation-frequency can be expressed in numbers directly.

Although in this specification the applications for medical purposes are placed on the foreground, it is evident that the use of the apparatus is not restricted to these applications, but that it can be utilized everywhere with great advantage in all such cases, where a local heating is required without that electrolyze arises, especially for industrial, chemical and bacteriological purposes.

I claim:

1. A device for diathermy comprising in combination means for generating high frequency currents of constant intensity including a triode and means for maintaining the electrode temperature constant during the treatment.
2. Device for diathermy comprising in combination a triode, a coil having one extremity connected to the grid of the triode, a coupling coil connected with the first coil, a connection between the cathode of the triode the first coil, and means for keeping the electrode temperature constant during the treatment, the oscillating circuit being connected to the triode in such a manner that with a strongly changing load the generating of the apparatus is not interrupted.
3. Device for diathermy comprising in combination, means for generating high frequency currents of constant intensity in-

cluding a triode and an electrode with edges that may be cooled during the treatment thereby that a metallic tube through which the cooling liquid flows is arranged around the edge.

4. Device for diathermy comprising in combination means for generating high frequency currents including a triode and an electrode, entirely or partially made of a metal or an alloy of low degree of hardness, which belongs to the tin group or is an alloy of metals of this group, the edges of which may be cooled during the treatment.

5. Device for diathermy comprising in combination means for generating high frequency currents including a triode, an electrode, means associated with the electrode in such a manner that the resistance, or thermoelectric force of said means varies with the temperature of the said electrode and controls the energy supply to or the heat discharge from the electrode.

6. Device for diathermy comprising in combination means for generating high frequency current including a triode, two electrodes, an inductively coupled coil connected with the two electrodes, one end of said coil being grounded.

7. Device for diathermy comprising in combination means for generating high frequency currents including a triode, a coupling coil inductively coupled to said means and a Röntgen tube connected to said coupling coil.

In testimony whereof I affix my signature.

FRANCISCUS HENRICUS REIJNDERS.
